LOCKING DEVICE FOR A VACUUM TUBE DISTRIBUTION SYSTEM
Louis F. Apel, 648 Atalanta, Webster Groves, Mo.
Filed Sept. 27, 1963, Ser. No. 312,268
3 Claims. (Cl. 243—28)
(Granted under Title 35, U.S. Code (1952), sec. 266)

The invention described herein may be manufactured and used by or for the Government for governmental purposes without the payment to me of any royalty thereon.

The present invention relates to the field of pneumatic tube systems and more particularly to locking devices for individually locking the terminal doors of a vacuum type, pneumatic tube distribution system.

The terminals of many vacuum tube distribution systems are furnished with doors which can be opened regardless of whether or not the system is shut down, thus it is possible to insert a carrier into the system when the vacuum within the system is inadequate to propel the carrier. This may occur for example when the vacuum pump is shut down or is not operating properly.

Accordingly, an object of this invention is to provide individual locking devices for the terminal doors of a vacuum tube distribution system responsive to the pressure within said system which prevents the opening of the terminal doors of said system when an inadequate vacuum exists therein.

The precise nature of the invention, its other objects and advantages are fully explained in the description which follows and in the drawings.

FIG. 1 is a perspective view showing the locking device installed in the terminal of a vacuum tube distribution system;

FIG. 2 is an exploded view showing the components of the preferred form of the locking mechanism;

FIG. 3 shows a latch plate which, together with the locking mechanism of FIG. 2 comprises the locking device; and

FIG. 4 is a sectional view of the locking mechanism taken along line 3—3 of FIG. 1.

FIG. 1 shows a terminal through which a tubular shaped carrier may be inserted into a vacuum tube distribution system. The carrier is thereafter propelled by differential air pressure to another terminal. The terminal shown in FIG. 1 comprises a terminal door frame 1 installed in building wall 2. Terminal door 3 is hingedly attached to wall 2 by spring loaded hinge 4. The spring of hinge 4 maintains terminal door 3 in a normally closed position. Terminal door 3 may be opened by handle 5 when it is desired to insert a carrier into the distribution system. Air seal strip 6 made of suitable resilient material surrounds the door frame and prevents the leakage of air into the system when door 3 is shut.

The locking device of the present invention comprises a lock mechanism 7 and latch plate 8. The lock mechanism is preferably installed on the inside of terminal door 3 at a point near the bottom and near the outside edge of the terminal door. Latch plate 8 is installed on the bottom floor of the terminal door frame at a location which is beneath lock mechanism 7 when the terminal door is closed.

Lock mechanism 7 comprises a lock body 7a consisting of a cap 9, a central portion 10 and a base 11. A circular, vertical bore 12 is provided in central portion 10. The upper portion 12a of this bore is cylindrical while the lower portion 12b is tapered. Circular plunger 13 is slidably received in the cylindrical portion 12a of vertical bore 12. Downward travel of plunger 13 is limited by the lower tapered zone 12b of vertical bore 12. Lock bolt 14 is attached to the center of circular plunger 13 and depends therefrom. Circular holes 15 and 16 are

2

provided in cap 9 and base 11 respectively of the lock body. Cap hole 15 is somewhat smaller than circular plunger 13; when the lock body is assembled the cap hole permits air to escape from above the plunger. Base hole 16 is sized to accommodate lock bolt 14 and is aligned therewith. When lock mechanism 7 is assembled and operating lock bolt 14 alternatively projects downward through the base hole 16 or is withdrawn further into the lock body.

Cap 9, central portion 10 and base 11 of the lock body have flat portions 9a, 10a and 11a, respectively, which form a single flat surface 7b when the lock body is assembled. The three elements of lock body 7a and plunger 13 may be made of any suitable material such as Plexiglas. The lock bolt may be made of steel rod adapted to be screwed into a threaded hole provided in the plunger. If made of Plexiglas the components of lock body 7a may be cemented together after the plunger and lock bolt are inserted in vertical bore 12. Flat surface 7b of the lock body may then be cemented to the inside surface of terminal door 3 or the lock body may be attached to the terminal door by any suitable means. Generally rectangular latch plate 8 comprises an inclined camming surface 8a, a vertical ledge 8b and a hole 8c sized and located to accommodate lock bolt 14 when the terminal door is closed and locked.

A circular passage 17 is drilled through terminal door 3 in alignment with circular passage 18 in the lock body; passage 18 opens in to the tapered portion 12b of vertical bore 12. Thus air at atmospheric pressure is always present in the tapered portion of the vertical bore and at the lower face of plunger 13.

The operation of the locking device will now be explained. When terminal door 3 is closed and an operating vacuum exists within the distribution system the top surface of plunger 13 is exposed through cap hole 15 to the reduced pressure of the system, while the lower surface of the plunger is exposed to atmospheric pressure through passages 17 and 18. The plunger therefore remains near the top of vertical bore 12; lock bolt 14 does not engage latch plate 8 and the door may be opened or closed at will. When on the other hand an operating vacuum does not exist in the system both the top and bottom surfaces of plunger 13 are exposed to atmospheric pressure. The plunger falls through the tapered portion 12b of vertical bore 12 and lock bolt 14 engages latch plate 8.

It will be apparent that a number of changes may be made in the locking device without departing from the spirit of the present invention. For example, latch plate 8 may be made without the lock bolt receiving hole 8c or it may be replaced by other suitable bolt engaging means which may be integral with the terminal door frame or which may be fabricated separately and attached thereto. Also lock body 7a need not be made in three parts as in the embodiment described above.

I claim:

1. A locking device to secure the terminal door of a vacuum tube distribution system when an operating vacuum does not exist within the system comprising:

a. a lock body affixed to the inside surface of the terminal door;
b. a lock bolt slidably received in said lock body;
c. lock bolt engaging means affixed within the terminal to the bottom of the door frame; and
d. means within said lock body responsive, when the terminal door is closed, to a change in the pressure differential between inside and outside of said terminal to selectively lower and raise said lock bolt into and out of engagement with said bolt engaging means.

2. A locking device to secure the terminal door of a

vacuum tube distribution system when an operating vacuum does not exist within the system comprising:

- a. a lock body, affixed to the inside surface of the terminal door, having a vertical bore formed therein;
- b. a plunger slidably received within said vertical bore;
- c. lock bolt engaging means affixed within the terminal to the bottom of the door frame;
- d. a lock bolt depending from said plunger and adapted to move therewith downward to a position in which it engages said lock bolt engaging means and upward to a position in which it is withdrawn from said lock bolt engaging means;
- e. passages formed in the terminal door and in said lock body adapted to expose the bottom of said plunger to atmospheric pressure; and
- f. an opening in said lock body adapted, when the terminal door is closed, to expose the top of said plunger to the pressure within the terminal.

5
10

3. The locking device described in claim 2 wherein:
- a. the lock body comprises a cap member, a central portion having a vertical circular bore therethrough said bore including a lower tapered zone, and a base portion having a vertical bore adapted to slidably receive said lock bolt; and
  - b. the lock bolt engaging means comprises a latch plate having a camming surface, a vertical ledge, and a hole adapted to receive said lock bolt.
